CLAIM

The ornamental design for a welding electrode holder assembly as shown and described.

DESCRIPTION

1. Welding electrode holder assembly

1.1 is a perspective view of a welding electrode holder assembly in use (assembled and flexed);

1.2 is a front elevational view thereof;

1.3 is a perspective view thereof;

1.4 is a top elevational view, the bottom, right and left views being symmetrical, thereof;

1.5 is a back elevational view thereof;

1.6 is an exploded view thereof;

1.7 is a top, back, right perspective view thereof;

1.8 is a top, front, right side perspective view of the first part, shown removed for clarity of disclosure;

1.9 is a top elevational view, the bottom, right and left views being symmetrical, thereof;

1.10 is a top, back, right side perspective view thereof;

1.11 is a front elevational view thereof;

1.12 is a back elevational view, thereof;

1.13 is top elevational view of the second part, the bottom, right and left views being symmetrical shown removed for clarity of disclosure;

1.14 is top, front, left side perspective view thereof;

1.15 is a top, back, left side perspective view thereof;

1.16 is a front elevational view thereof;

1.17 is a back elevational view thereof;

1.18 is a top, front, left side perspective view of the third part being shown removed for clarity of disclosure;

1.19 is a top, back, left side perspective view thereof;

1.20 is a front elevational view thereof;

1.21 is a top elevational view, the bottom, right and left views being symmetrical, thereof;

1.22 is a back elevational view thereof;

1.23 is a top, front, left side, perspective view of the fourth part being shown removed for clarity of disclosure;

1.24 is a top, back, left side perspective view thereof;

1.25 is a top elevational view, the bottom, right and left views being symmetrical, thereof;

1.26 is a front elevational view thereof;

(Continued)

1.27 is a back elevational view thereof;
 1.28 is a top, back, right-side perspective view, of the fifth part being shown removed for clarity of disclosure;
 1.29 is a top elevational view, the bottom, right and left views being symmetrical, thereof;
 1.30 is a front, elevational view thereof;
 1.31 is a top, front, right-side, perspective view thereof;
 1.32 is a back elevational view thereof;
 1.33 is a front view, of the sixth part being shown removed for clarity of disclosure;
 1.34 is a back, top, perspective view thereof;
 1.35 is a back, elevational view thereof;
 1.36 is a rear perspective view thereof; and
 1.37 is a top elevational view, the bottom, right and left views being symmetrical, thereof.
 The present design is for a welding electrode holder assembly; it contains an assembly of six parts that are shown removed for clarity of disclosure; these parts have top/bottom/left/right symmetry; the dashed lines of reproduction 1.1 forms no part of the claimed design; the dot-dashed lines of reproduction 1.6 are only to show an exploded view and form no part of the claimed design.
